UNITED STATES PATENT OFFICE

OLIVER H. LOOMIS, OF ILION, NEW YORK, ASSIGNOR TO REMINGTON ARMS COMPANY, INC., A CORPORATION OF DELAWARE

FIREARM

Application filed February 16, 1925. Serial No. 9,582.

This invention relates to firearms, and particularly to interlocking devices for various elements of the fire control mechanism. For the purpose of illustration, I have shown my invention as applied to a firearm of the type disclosed in U. S. Patent 1,143,170, June 15, 1915 to J. M. Browning, but it is to be understood that the invention is of general application and not limited to the particular gun illustrated.

In guns of the type disclosed in the Browning patent, shells or cartridges are stored in a tubular magazine extending longitudinally beneath the barrel, and are transferred one at a time to the chamber. The shell in the chamber is fired by the impact therewith of a firing pin driven forward by a blow from a pivoted hammer. The hammer is held in cocked position by the engagement with a notch therein of the nose of a sear integral with the trigger.

When the gun has been fired the functions of unlocking and retracting the breech block, ejecting the empty shell, cocking the hammer, transferring a fresh shell from the magazine to the chamber, and advancing and locking the breech block, are all performed by reciprocating an action bar attached to the forearm, the movement of the action bar and forearm being first rearward, then forward to initial position. Since guns of this type are fired from the shoulder, and are usually held against the shoulder by means of the forearm, it is necessary that the action bar be locked against rearward movement when the gun is in ready-to-fire condition. To this end the Browning patent above identified provides an action bar lock, and a control device therefor, associated with the hammer, which prevents retraction of the action bar while the hammer is cocked, unless the lock is released by manipulation of an extending finger piece.

It is likewise desirable that means be provided for preventing the fall of the hammer until the action bar has been fully advanced, thereby closing the breech and locking the breech block. The hammer is concealed in the receiver, and in order to cock the hammer it is necessary to fully operate the action. If the hammer can be moved forward as the ac-

tion is closed by holding the trigger depressed or by other manipulation, the hammer can be cocked only by again operating the action and thereby ejecting the unfired shell in the chamber.

Moreover, if the hammer can be released to move forward when the breech block is not closed and locked, there is danger that a shell or cartridge may be fired with the breech block in this condition, with serious injury to the mechanism or the shooter, or both. This is a contingency which must be carefully guarded against.

In the Browning patent above identified a device associated with the action bar lock engages the hammer and holds it in cocked position during the greater part of the forward movement of the breech block. However, the construction of this device is such that the hammer is released before the breech block is locked. Moreover, it is effective only if the action bar has been fully retracted. Assume that a fresh shell has been placed in the chamber and the breech closed and locked by one complete operation of the action bar. If the action bar lock is now withdrawn by manipulation of the finger piece provided for this purpose, and the action bar partially retracted, the hammer is then free from the locking device, and may be released in any position of the breech block by merely pressing the trigger. The action may then be closed with the hammer not cocked.

One object of the present invention is to provide an improved form of action bar locking device.

A further object of the invention is to provide an improved means for blocking the movement of the hammer during the forward movement of the action bar.

A further object of the invention is to provide an improved interlock between hammer and trigger, effective to prevent the forward movement of the hammer while the trigger is held depressed, and likewise effective to prevent depression of the trigger during a certain part of the movement of the hammer.

A further object of the invention is to provide means for preventing the release of the hammer from the sear when the breech is

not entirely closed, this means being controlled solely by the position of the action bar and not dependent on a certain sequence of operations of the mechanism.

With these and other objects in view my invention consists in the novel combinations and arrangements of parts which are illustrated in the drawings and will be hereinafter described.

10 In the drawings:

Fig. 1 is a fragmentary side elevation, partly in section, of the receiver of a gun embodying my invention, showing the action closed, the hammer cocked, and the associated parts in the corresponding positions.

15 Fig. 2 is a sectional elevation of the trigger plate, action bar slide, and a part of the breech block, the slide being in its rearmost position.

20 Fig. 3 is a view similar to Fig. 2 showing the slide passing out of engagement with the hammer, and the hammer and trigger lock in effective position.

25 Fig. 4 is a view similar to Fig. 2 showing the hammer cocked and the action bar slide forward and locked.

Fig. 5 is a plan view of the trigger plate and parts mounted thereon.

30 Fig. 6 is a detail of the trigger locking sear.

Fig. 7 is a vertical section thru the trigger plate showing the hammer engaged by the trigger controlled hammer latch.

35 Fig. 8 is an inverted plan view of the action bar slide.

The fire control mechanism is housed in a receiver or frame 10 having a bottom opening 11, thru which the fresh shells are inserted into the magazine 12 and the empty shell cases are ejected. Slidably mounted in guide 40 channels 13 in the sides of the frame is an action bar slide 14 attached by pin 15 to an action bar 16 which is connected at its forward end of the usual forearm (not shown).

45 The action bar slide 14 is thus adapted to be reciprocated by manipulation of the forearm, and the reciprocation of the action bar controls the operations incident to ejecting the empty shell case from the chamber and feeding the fresh shell from the magazine to the chamber in the manner which will be hereinafter described. The breech block, indicated generally by 17, comprises longitudinal recesses which contain the extractor 18 50 and the firing pin 19. The firing pin is held in place by cross pin 20, and is retracted from engagement with the head of the shell by spring 21. A recess cut in the top of the frame 10 forms a recoil shoulder 22 adapted

55 to engage the end 23 of the breech block, thereby locking the breech block in breech closing position until it is lowered by movement of the action bar.

60 A lug or hook 24 projecting downwardly from the breech block is adapted to engage a

recess 25 in the action bar slide 14 as clearly shown in Fig. 2. When the action bar is drawn rearwardly the forward edge of hook 24 is engaged by an inclined cam face 26 on the action bar slide whereby the breech block 70 is lowered out of engagement with recoil shoulder 22. Further rearward movement of the action bar draws the breech block rearwardly, breech block and the action bar slide moving together. On the forward movement of the action bar, the action bar slide and breech block move together until the breech is closed and the end 23 of the breech block is in front of recoil shoulder 22. As the forward movement of the action bar is 80 completed the inclined cam face 27 of action bar slide 25 raises the breech block into engagement with recoil shoulder 22.

The means for retaining shells in the magazine, and for releasing them one at a time to 85 be transferred to the chamber comprises a retainer 28, normally in engagement with the head of the rearmost shell in the magazine, but adapted to be withdrawn and release the rearmost shell near the end of the rearward 90 movement of the action bar slide. A cartridge stop lever 29 is adapted to be rocked about its horizontal pivot into position to engage the head of the second shell in the magazine and hold this shell until the retainer 28 is restored to effective position.

The means for transferring the shell released from the shell retaining devices to position to be moved into the chamber by the head of the breech block, comprises a carrier device, pivoted at 30 to the sides of the frame 10. This carrier device comprises longitudinally extending spring fingers 31 connected at their rear ends by a cross piece 32. When the breech is closed the carrier fingers 100 are in the position indicated in Fig. 1. As the action bar and breech block begin to move rearwardly, the ends of fingers 31 engage cams 33 on the sides of the breech block, moving the fingers upwardly into a recess 34 105 in the top of the receiver. In the further rearward movement of the breech block, the empty shell is withdrawn from the chamber beneath the carrier fingers. As the breech block and action bar slide reach the end of 110 their rearward movement, cross piece 32 is engaged by cam face 36 at the rear of the action bar slide and the carrier fingers are quickly moved downwardly to eject the empty shell cases, and to receive a fresh shell 115 from the magazine. As the action bar slide reaches the end of its rearward movement the rearmost shell in the magazine is released from retainer 28 and is pushed out of the magazine on to the carrier fingers 31 by the magazine spring. As the action bar slide begins to move forward, inclines 37 on the carrier fingers are engaged by cam faces 38 120 on the action bar slide, and the carrier fingers, with the shell which has been placed

125

thereon, are elevated to the position shown in Fig. 1. As the breech block moves forward, the shell is pushed into the chamber by the breech block, the carrier fingers being spread to permit the passage of the breech block, and dropping behind the cam shoulders 33. The shell retaining and transferring devices are more fully described in the Browning patent above identified.

- 10 At the rear of the cartridge or shell opening 11 is a trigger plate 40, which carries certain elements of the fire control mechanism, including a hammer 41. The hammer is pivoted on a transverse pin 42, and is connected by means of a pin 43 with a rearwardly extending hammer link 4. A hammer spring 45 lies in a suitable recess in the trigger plate, and a spring follower 46 engages the end of hammer link 44.
- 20 A trigger 47 pivoted in the trigger plate on trigger pin 48, comprises a forwardly extending arm or sear 49, adapted to engage a hammer notch 50, and is pressed toward hammer engaging position by sear spring 51.
- 25 The trigger likewise comprises an upwardly extending heel 52 adapted to engage the trigger locking safety stud 53.

An action bar locking member 54, pivotally mounted on the trigger pin 48, is urged 30 to rotate counter clockwise (Figs. 2, 3 and 4) by action bar lock spring 55, into the position shown in Figs. 1 and 4, in which the nose 56 of the action bar lock engages the heel 561 of the action bar slide, locking the slide 35 against retraction. The means for automatically rocking the action bar slide to ineffective position when the gun is fired, comprises a spring member 57 having an end 571 which extends transversely over the hammer link 44. Spring member 57 is secured 40 to the lock at its forward end, and passes under a short stud 58 on the lock. The hammer link comprises a cam lug 59 which, on the forward movement of the hammer engages the lateral extension of the spring member 57, moving it upward. The tension on 45 this member is then sufficient to overcome the action bar block spring 55, and the action bar lock is rotated clockwise to ineffective position. Means are provided for manually moving the action bar lock to ineffective position, comprising an extending finger piece 60 integral with the action bar lock.

50 My invention contemplates interlocking devices effective to prevent release of the hammer from cocked position whenever the action bar slide is out of its forward or "home" position, in which position it holds the breech block locked, as shown in Fig. 1. 55 These interlocking devices comprise first, a sear controlled by the action bar lock and acting to block the movement of the trigger whenever the action bar lock is not in effective position; and second, a latch constituting an interlock between hammer and trig-

ger. The trigger locking device controlled by the action bar lock is constructed as follows:

A lever or safety sear 61, pivoted in the trigger plate at 62 comprises a forwardly extending toe 63 which underlies the rear end or tail of the action bar lock, and a laterally extending foot 64 which overlies the trigger. The safety sear is urged into engagement with the tail of the action bar lock 70 by a spring 65. When the action bar lock is in ineffective position (Fig. 3) its rear end is raised, and the lower end of the safety sear is moved forward by the spring 65 to a position in which it is effective to block movement of the trigger to hammer releasing position. But when the nose of the action bar lock is raised by spring 55 into effective position, its tail engages the safety sear moving it rearwardly and downwardly. The foot 64 75 is thereby moved opposite a groove or depression 66 in the trigger. The trigger is then free to move to hammer releasing position, the groove 66 embracing the foot 64. The interlock between hammer and trigger 80 comprises a latch 66 pivoted on a cross pin 67, which pin also serves as a stop for the action bar lock. The latch 66 comprises a heel 661 adapted to engage the trigger, and a nose 68 adapted, when heel 661 is raised 85 by pressing the trigger, to engage a ledge or lip 69 on the hammer. The engaging surfaces of the lip 69 and the nose 68 are beveled, so that the hammer will cam the latch back and move past it unless the latch is positively held in hammer engaging position. Above the nose 68 the latch comprises an arcuate face 70 adapted to contact with the edge of the lip 69, as this part of the hammer moves past said face. The engagement of the face 70 90 with the lip 69 effects the movement of the trigger to position in which the sear will engage the hammer notch, as the hammer is drawn backward, and again as it moves forward to normal cocked position.

The operation of my improved interlocking devices is as follows: Assume that the gun is cocked and the breech closed. The parts of the fire control mechanism are then in the position shown in Figs. 1 and 4. The hammer is held by the sear, the nose of the action bar lock is pushed upward by the action bar lock spring into the path of the heel of the action bar slide, thus locking the action bar. The safety sear is pushed rearwardly 100 against the tension of its spring by the tail of the action bar lock, so that the foot 64 is opposite the groove in the trigger, and the trigger is free to move.

In order to retract the action bar to unlock and open the breech, it is necessary to press the finger piece 60 rearwardly, thereby rocking the nose of the action bar lock out of the path of the action bar slide. This movement however, raises the heel of the action bar 105

lock out of engagement with the safety sear. The safety sear is thereupon moved forward by its spring, the foot moving out of alignment with the groove in the trigger and blocking the trigger against the movement necessary to release the hammer from the sear. The trigger is thus blocked against the slide holds the nose of the action bar lock is ineffective. If the action bar is now partially retracted the bottom of the action bar slide holds the nose of the action bar lock depressed and the safety sear remains in trigger locking position. The trigger is again released for operation only when the action bar is fully advanced and the action bar lock rocked by its spring to effective position.

Assume now that the gun has been fired and the action bar is given one full operation for the purpose of ejecting the empty shell, and reloading. As the action bar slide moves rearwardly it carries the hammer back to the position shown in Fig. 2; in the normal operation of the gun as the action bar moves forward the hammer also moves forward to the Fig. 1 position, in which it is engaged by the sear. Suppose, however, that the shooter attempts to hold the trigger back while operating the action. The action bar may be operated but the hammer will remain cocked, the mechanism for effecting this result operating as follows: As the action bar is retracted the action bar slide 14 moves rearwardly out of engagement with the nose 56 of the action bar lock, to the position shown in Fig. 2. In this position the heel of the action bar lock engages and depresses the safety sear 61 so that the foot 64 registers with the trigger notch 65 and the trigger is free from the locking action of the safety sear. However, in its cocking movement the hammer engages and rocks the hammer latch 66, which, thru the shoulder 661 forces the finger engaging part of the trigger forward, thereby warning the shooter that the trigger should be released. But if the shooter continues to draw rearwardly upon the trigger, again depressing it, the nose 68 of the hammer latch 66 engages with the ledge 69 on the hammer, thereby retaining the hammer in the position shown in Fig. 7 as long as the trigger is held depressed. When the trigger has been released and the hammer starts forward, the arcuate face 70 of the latch is engaged by the end of the hammer, thus preventing a second depression of the trigger until the hammer clears said arcuate face, and before this occurs, the action bar slide 14 moves into engagement with the nose 56 of the action bar lock and rocks said lock out of engagement with the safety sear 61, thereby permitting spring 65 to swing the safety sear into trigger locking position. The hammer thus comes to rest in engagement with the nose 49, that is, in its normal cocked position.

Variations in the structure illustrated and described may be resorted to, it being understood that the embodiment of the invention herein shown is illustrative rather than restrictive, and that the invention is limited only by the scope of the appended claims.

I claim:

1. In a fire control mechanism, in combination, a trigger plate, a hammer and a trigger pivoted in said trigger plate, and a trigger controlled hammer latch pivoted in said plate and adapted to engage said hammer when said trigger is held depressed.
2. In a fire control mechanism, in combination, a hammer, a trigger controlling said hammer, a pivoted interlock adapted to alternately block the forward movement of the hammer and the hammer releasing movement of the trigger.
3. In a fire control mechanism, in combination, a hammer, means for retracting said hammer, a trigger mechanism adapted to retain said hammer in cocked position, but to release said hammer when depressed, and an interlock adapted to engage said hammer when said trigger is held depressed during the retraction of said hammer, and to prevent hammer releasing movement of said trigger during a part of the movement of said hammer.
4. In a fire control mechanism in combination a frame, an action bar, a pivoted hammer, a pivoted trigger comprising a nose adapted to engage and hold said hammer, an action bar lock pivoted concentric with said trigger, a substantially vertically disposed trigger lock separately pivoted in said frame and overlying said trigger, and a rearwardly extending projection on said action bar lock adapted to engage a portion of said trigger lock.
5. In a fire control mechanism, in combination, an action bar, a pivoted hammer, a pivoted trigger comprising a forwardly extending sear nose adapted to engage said hammer, a hammer spring, a strut connecting said hammer and hammer spring, an action bar lock pivoted concentric with said trigger and controlled by said strut, a trigger lock controlled by said action bar lock, and a hammer lock controlled by said trigger.

OLIVER H. LOOMIS.
